(57) **CLAIM**

The ornamental design of an electronic vaporizer mouthpiece, substantially as shown and described.

DESCRIPTION

FIG. 1 is a top front perspective view of an electronic vaporizer mouthpiece in accordance with the present design; FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines in the Figures show portions of the electronic vaporizer mouthpiece which form no part of the claimed design. The oblique lines in the drawings indicate transparency.
